UNITED STATES PATENT OFFICE.

GUSTAVO VINCON, OF TURIN, ITALY.

BREECH-CLOSING MECHANISM FOR AUTOMATIC FIREARMS.

Application filed July 13, 1926, Serial No. 122,138, and in Italy July 16, 1925.

This invention has for its object certain improvements in the breech closing mechanism for automatic fire arms having a fixed barrel and a rotating breech block whereby

5 a better working and a longer life of the fire arm and a considerable economy in its construction are obtained.

Said improvements consist substantially in providing on the head portion of the breech

10 block two retaining shoes provided with inclined surfaces engaging with corresponding inclined shoulders provided in a member secured to the cradle. Said shoulders are so inclined as to permit the rotation of

15 the breech block towards its open position owing to the reaction resulting thereon when firing. The rotation towards the closed position of the breech block is effected by a plunger disposed inside the breech block and

20 subjected to the action of a return spring, said plunger being provided with shoes having inclined surfaces engaging in a correspondingly inclined groove provided in the breech block, this latter being thus caused

25 to rotate at a suitable moment towards its closed position. The plunger is blocked against rotation through a guiding rectilinear groove provided in the cradle in which its shoe slides, and the breech block is pro-

30 vided with a lever whereby it is maintained in permanent engagement with the plunger except during the short movement corresponding to the rotation towards the open and closed position, said lever being auto-

35 matically disengaged at the beginning of said movement.

The invention consists substantially in the combination of the following members:

Shoes for the closure of the breech block 40 provided on the head portion of the breech block;

Shoulders for the breech block shoes provided in a member secured to the cradle, a plunger (acted upon by a return spring) effecting the rotation of the breech block and provided to this end with a shoe guided along a straight line in the cradle and acting through its inclined side on a correspondingly inclined surface of the breech block, 50 having the purpose of effecting the rotation of this latter towards its closed position at the desired moment.

A lever connecting the breech block with the plunger its disengagement being automatically effected through suitable means se-

cured to the cradle only during the short movement corresponding to the rotation of the breech block towards its closed and open position respectively.

The following advantages are obtained by 60 using this invention:

(1) A more satisfactory working of the fire arm owing to the arrangement of the shoes on the head portion of the breech block in combination with the lever connecting the 65 breech block with the plunger relieving the rectilinear guide of the plunger shoe from any pressure which, as is well known, would cause a braking of the parts and a possible blocking of the arm due to a gripping action. 70

(2) An easier and smoother hand arming operation of the breech block due to the fact that the plunger shoe to be operated effects only a rectilinear motion.

(3) A considerable economy of construction, as the cradle may be constructed of ordinary steel requiring no special treatment as the shoulders on which the breech block shoes act (that must necessarily be of high resistance steel) are obtained in a small detached piece and are therefore cheap and of such form and size that they will not undergo any permanent deformation during the treatment thus reducing the losses. Moreover the rectilinear guide of the plunger 85 shoe not being subjected to a noticeable pressure as above stated, the cradle may be constructed of ordinary steel.

(4) A long life of the fire arm as the shoulders of the breech block shoes can be 90 replaced while the cradle lasts longer, having no parts subjected to hard wear.

The annexed drawings show by way of example and diagrammatically an improved automatic fire arm constructed in accordance 95 with this invention.

Figure 1 is an axial longitudinal section, the breech block being in the open position and the connecting lever being engaged in the plunger.

Figure 2 is a cross section on line 2-2 of Figure 1.

Figure 3 is a similar section as Figure 1, the breech block being shown when starting its movement towards its closed position and 105 the lever connecting same with the plunger being on the point of disengagement.

Figure 4 is a cross section on line 4-4 of Figure 3.

Figure 5 is a similar section as Figures 110

1 and 3, the breech block being closed and the connecting lever fully disengaged from the bolt.

Figure 6 is a cross section on line 6—6 of Figure 5.

Figure 7 is a detailed view of the breech block.

Figure 8 is a detailed view of the plunger. The cradle 1, which forms the casing for

10 the breech mechanism has mounted in its forward end a piece 2 of high resistance steel, said piece being provided with rectilinear slots 3 entering a groove 4 having inclined shoulders. The breech-block 5, 15 mounted in the casing, is provided at its forward end 6 with shoes 7, designed to pass through the slots 3 and engage said inclined shoulders thereby rotating the block for effecting a closure of the latter. The rear 20 portion of the breech-block 5 is formed with a cylindrical chamber 5', in which is reciprocally mounted a plunger 12. This latter is subjected to the action of the return spring 17 and is provided with a shoe 11 sliding in 25 a rectilinear guide 10 of the cradle and passes through an inclined groove 14 of the breech block (Figure 7) in which it is permanently engaged. The rectilinear portion 13 of the groove 14 serves only for the mounting of 30 the bolt into the breech block.

The plunger 12 is provided at its head portion with a slot 15 in which the lever 8 of the breech block will engage, said lever being pressed by its spring during the whole rectilinear stroke of the breech block.

35 A tooth 9, secured to the cradle in a suitable position, raises automatically the lever 8 from the slot 15 when the breech block is starting its movement towards its closed position and the bolt slot 16 in which said lever lies holds the plunger and the breech block disengaged during the whole closing or opening action of this latter (Figures 5 and 6).

The fire arm works as follows:

40 When firing, the breech block is caused to rotate by the inclined shoulders 4 of the member attached to the cradle, while the plunger which is prevented from rotating by the rectilinear groove 10, is brought back- 45 wards in respect of the breech block (Figures 5 and 1) through the inclined groove 14 of the breech block.

The lever 8 slides in the slot 16 and at the end of the rotation of the breech block 50 towards its open position snaps into the slot 15 (Figures 6 and 2) connecting the breech block and the plunger to each other; the

breech block and bolt, thus connected, will thereupon effect the recoil stroke, during which the shell is expelled and the feeding forward stroke takes place until the tooth 9 disengages the lever from the slot 15 of the plunger (Figures 3 and 4) and the breech block, disengaged from this latter, rotates towards its closing position (Figures 5 and 6).

On the shoe 11 of the plunger are provided the known means for arming the breech block; said operation is made easier owing to the fact that the plunger effects only a rectilinear motion.

What I claim is:

1. In an automatic fire-arm the combination of a cradle having inclined shoulders at its forward end, a slidable and rotatable breech-block having shoes formed thereon to engage said shoulders, said breech-block having a cylindrical portion on its rear end forming a chamber, a plunger slidably mounted in the latter, a spring for pressing the plunger against the bottom of the chamber, a shoe on the plunger slidable in a rectilinear guide on the cradle and engaging an inclined groove in the breech-block, means for preventing relative rotation of the breech-block and plunger during the recoil and return motion, and means to release the breech block from the plunger at the end of the rectilinear return stroke for allowing the breech block to rotate to its closed position.

2. In an automatic fire-arm the combination of a cradle having inclined shoulders at its forward end, a slidable and rotatable breech-block having shoes formed thereon to engage said shoulders, said breech-block having a cylindrical portion on its rear end forming a chamber, a plunger slidably mounted in the latter, a spring for pressing the plunger against the bottom of the chamber, a shoe on the plunger slidable in a rectilinear guide on the cradle and engaging an inclined groove in the breech-block, a lever on the breech-block having an arm extending into said chamber, to engage the plunger at the end of the rotation of the breech-block to its open position for connecting the breech-block and plunger, and means on the cradle to move the lever out of engagement with the plunger at the end of the forward stroke of the breech-block to allow the latter to rotate to its closed position.

In testimony that I claim the foregoing as my invention, I have signed my name.

GUSTAVO VINCON.
